UNITED STATES PATENT OFFICE.

BIAGIO MARTINI, OF PITTSBURGH, PENNSYLVANIA.

RAILROAD SWITCHING DEVICE.

Application filed October 11, 1926. Serial No. 140,788.

This invention relates to railway switching devices, and more in particular to devices to be used at the point of junction where two tracks converge to form a single 5 track.

The primary object of this invention is to provide a new and improved switching device which takes the place of the rigid railway-frogs now in common use and at the 10 same time greatly reduces the liability to derailments, as now exists wherever rigid frogs are used. Another object of this invention is to do away with the so-called guard-rails and correlated parts which must 15 invariably be used in connection with ordinary frogs to prevent, as well as possible, derailments. Still another object of this invention is the provision of a switching device which may be installed at low cost, is 20 very simple in construction and operation and in which the parts most exposed to wear and tear may be easily and quickly renewed without discarding any of the other parts 25 of the switching device that are not exposed to as great an extent to wear. Additional features and advantages of this invention will appear in the course of the following description considered in connection with the accompanying drawings forming part of 30 this application, and in which:

Fig. 1 is a plan view showing the junction of two railroad tracks into one, at which junction my switching device has been installed to replace the usual railroad-frog 35 now employed.

Fig. 2 is a fragmentary sectional view taken substantially on line 2-2 in Fig. 1.

Fig. 3 is a sectional view taken on line 3-3 in Fig. 2.

Fig. 4 is an enlarged fragmentary view showing my switching device in the same position as indicated in Fig. 1.

Fig. 5 is a similar view, showing my switching device in the opposite position to 45 that shown in Fig. 1.

Fig. 6 is a plan view of a section of a track-junction showing my switching device in place and the mechanism for operating it in conjunction with other parts of the switch- 50 ing mechanism.

Fig. 7 is a plan view of a track-junction built according to the usual practice now in vogue and in which a rigid railway-frog and the usual guard-rails are shown.

55 In view of the fact that the main object of my invention is to eliminate the use of

costly and rapidly deteriorating railway-frogs, I have chosen to call my device a shift-frog, to distinguish it from other switching elements employed in everyday railway construction. 60

Reference being had to the drawings, the shift-frog is composed of two principal parts, namely the movable half 1 and the stationary half 2. The movable half comprises the two converging rail sections 3 and 4 which are held at their junction by means of the wedge-shaped filler-block 5. The rails are secured to the main portion of the track by means of the splice-bars 6 which permit a slight angular and horizontal movement of the rail elements 3 and 4. The latter rest freely upon the specially built tie-plates 7 upon which are secured by means of the rivets 8 the rail-braces 9 which serve 70 also as stops for limiting the lateral movements of the rails to the required amount. Rail 3 is rigidly secured to the filler-block 5, whereas rail 4 is held against said block in such a manner as to permit a certain sliding 75 movement of said rail against the block, in order to enable the simultaneous lateral shifting of both rail elements. A study of Figs. 1 and 5 will show that if the rail elements 3 and 4 are properly cut to be in line 80 when the shift-frog is in the position shown in Fig. 5, an angular shifting of said rails into the position illustrated in Fig. 1 will cause the rail 4 to protrude beyond the rail 3 and the apex of the filler-block 5. In order 85 to provide for this relative movement of the rails 3 and 4, they are secured to the filler-block 5 in the manner shown especially in Figs. 2 and 3. As shown therein, through-bolts 10 are inserted in registering apertures 90 11, 12 and 13 provided respectively in the rail 3, the filler-block 5 and the rail 4. The apertures in the rail 3 and the filler-block 95 are circular and fit snugly about the bolts, whereas the apertures 13 in the rail 4 are elongated and enlarged to provide for the insertion and longitudinal play of the sleeves or bushings 14 the length of which is slightly greater than the thickness of the web of the rail, to produce a small clearance 100 whereby any clamping of the web of the rail by the bolts is prevented and the sliding of said rail on the filler-block assured. 105

The stationary half of the shift-frog consists of the converging rails 15 and 16 which are permanently secured on the ties 17 by means of the usual spikes 18. These rails 110

are also rigidly secured by means of bolts 19 to the filler-block 20 which serves to hold the converging ends of said rails in proper spaced relation to enable the passage of the 5 wheel-flanges of the rolling-stock.

In Fig. 6 is shown one method of actuating the shift-frog in connection with the other movable component parts used in a 10 track-junction. As shown, this junction consists of the tracks 21 and 22 which converge into the single track 23. The switching mechanism for this junction is composed of the shift-frog and correlated parts of my invention and of the standard split-switch 24 comprising the two movable switch-feathers 25 and 26. The shift-frog and split-switch are operated simultaneously and in the same 15 direction by means of the connecting-rods 27 and 28 which are hingedly connected in any 20 desired manner to said frog and split-switch. The other ends of the connecting-rods are rockably connected to the bell-crank-levers 29 and 30, respectively, which are actuated by a common pull-rod 31. The latter may be 25 moved back and forth by means of the air-cylinder 32 disposed alongside the railroad track and which preferably is connected to 30 a distant switch-tower (not shown) by means of piping indicated diagrammatically 35 by numeral 33. This type of air-cylinder is now commonly used in railroad engineering for the distant control of movable switching devices, and for that reason a detail description is not thought necessary. In this figure 40 I have also indicated in dot and dash lines the course that would be taken by a railroad car or locomotive if the split-switch and the shift-frog were placed in the manner shown.

Fig. 7 has been drawn to better visualize 45 the structural differences between the common construction and the one which forms the subject matter of this application. As is well known, the rigid frogs 34 used at the present time are subject to tremendous wear, especially at the point, and in order to increase the useful life of said frogs, they are made of very expensive alloy-steels of great hardness. Also, in order to prevent any jumping 50 of the wheels of the rolling stock at the point of the frog, it is imperative that the guard-rails 35 and 36 be used to guide said wheels into the right tracks. When rigid frogs made of alloy-steel are worn at the most exposed 55 parts, it becomes necessary to practically discard the whole frog because the nature of the steel used does not allow its reheating and forging without greatly reducing its wearing quality.

As compared with rigid frogs, the wear on 60 the shift-frog of my invention is limited practically to the component rail elements 3 and 4 and the latter may readily be renewed on the site, if necessary, with the help of the 65 tools usually carried by the track repair-men.

Moreover, the rail-elements are of the same material as the common rails used for the tracks and, on account of their relative shortness may often be cut from pieces of rails which otherwise would be considered 70 as scrap. It has also been stated that the rapid wear of solid frogs occurs mainly at the point of the frog where the change of direction occurs, in my device there is no such vulnerable point, on the contrary the 75 rail-elements 3 and 4 offer at the point of change of direction practically the full cross-section and the wheels pass over this point with the same ease as they pass over the small 80 gaps which appear at the places where the rail-lengths are spliced together. For these reasons my device is not only more durable but also much safer.

As will be understood, there may be slight 85 changes made in the construction and arrangement of the details of my invention without departing from the field and scope of the same, and I intend to include all such variations, as fall within the scope of the appended claims, in this application in 90 which the preferred form only of my invention has been disclosed.

I claim:

1. In a shift-frog, a stationary half and a 95 movable half comprising two converging rail-elements and a filler-block positioned at the point of convergence of said rail-elements; means for securing one of said rail-elements rigidly to said filler-block; means for securing the other rail-element for longitudinal sliding movement along said filler-block; connecting means for hingedly securing the divergent ends of said rail-elements to the rails of a railway track, and means for rotating said movable half in a 105 horizontal plane about said connecting-means.

2. In a shift-frog, the combination of a 110 stationary half comprising two stationary converging rails and a filler-block positioned at the point of convergence of said rails; means for securing said rails rigidly to said filler-block; a movable half comprising two converging rail-elements and a movable 115 filler-block positioned at the point of convergence of said rail-elements; unitary means for securing one of said rail-elements rigidly to said movable filler-block and for securing the other rail-element for longitudinal sliding movement along said movable 120 filler-block; connecting means for hingedly securing the divergent ends of said rail-elements to the rails of a railway-track, and means for rotating said movable half in a 125 horizontal plane about said connecting-means.

3. In a shift-frog, the combination of a 130 stationary half comprising two stationary converging rails and a filler-block positioned at the point of convergence of said rails,

- means for securing said rails rigidly to said filler-block; a movable half comprising two converging rail-elements and a movable filler-block positioned at the point of convergence of said rail-elements; unitary means for securing one of said rail-elements rigidly to said movable filler-block and for securing the other rail-element for longitudinal sliding movement along said filler-block; connecting means for hingedly securing the divergent ends of said rail-elements to the rails of a railway-track; means for rotating said movable half in a horizontal plane about said connecting means, and means for limiting the amount of rotation of said movable half.
4. In a shift-frog, the combination of a stationary half comprising two stationary converging rails and a filler-block positioned at the point of convergence of said rails; means for securing said rails rigidly to said filler-block; a movable half comprising two converging rail-elements and a movable filler-block positioned at the point of convergence of said rail-elements; unitary means for securing one of said rail-elements rigidly to said movable filler-block and for securing the other rail-element for longitudinal sliding movement along said filler-block; connecting means for hingedly securing the divergent ends of said rail-elements to the rails of a railway-track; means for rotating said movable half in a horizontal plane about said connecting means, and stationary rail-braces adapted to simultaneously limit the amount of rotation of said movable half and support the rail element engaged thereby.
5. In a shift-frog comprising a stationary half and a movable half, the combination of a movable filler-block for securing the converging rail-ends of said movable half, said filler-block being rigidly connected to one of said rail-ends and connected for longitudinal sliding movement to the other converging rail-end.
6. In a shift-frog of the character described, a movable half comprising two converging rails; a filler-block positioned at the point of convergence of said rails; a through-bolt for holding said parts together; one of said rails and said filler having registering apertures fitting closely about said bolt and the other rail having an oblong aperture also engaged by said bolt, whereby said other rail may slide longitudinally along said filler-block.
7. In a shift-frog of the character described, a movable half comprising two converging rails; a filler-block positioned at the point of convergence of said rails; a through-bolt for holding said parts together; one of said rails and said filler having registering apertures fitting closely about said bolt and the other rail having an oblong aperture also engaged by said bolt whereby said other rail may slide longitudinally along said filler-block, and means to prevent the rigid clamping of said other rail to said filler-block.
8. In a shift-frog of the character described, a movable half comprising two converging rails and a filler-block positioned at the point of convergence of said rail; a through-bolt for holding said parts together; one of said rails and said filler-block having registering apertures fitting closely about said bolt and the other rail having an enlarged and oblong aperture also engaged by said bolt, and a bushing fitting about said bolt and positioned in said enlarged aperture, said bushing being longer than the thickness of the web of said other rail to prevent the rigid clamping of the latter against said filler-block.

In testimony whereof I affix my signature.

BIAGIO MARTINI.
